UNITED STATES PATENT OFFICE.

WILLIE I. PALMER, OF WHEATLAND, WYOMING.

DIVIDERS.

1,264,552.

Specification of Letters Patent. Patented Apr. 30, 1918.

Application filed January 12, 1916. Serial No. 71,707.

To all whom it may concern:

Be it known that I, WILLIE I. PALMER, a citizen of the United States, residing at Wheatland, in the county of Platte, State of Wyoming, have invented certain new and useful Improvements in Dividers; and I do hereby declare the following to be a full, clear, and exact description of the invention, such as will enable others skilled in the art to which it appertains to make and use the same.

The present invention is directed to improvements in dividers, and has for its object to so construct a device of this character to accurately ascertain the distance between the points of the legs thereof.

A further object of the invention is to provide a divider having a graduated bar carried thereby to indicate accurately the distance measured between the points of the legs thereof.

A still further object of the invention is to provide a novel means for locking the legs of the device in their adjusted positions.

With these and other objects in view, this invention resides in the novel features of construction, formation, combination and arrangement of parts to be hereinafter more fully described, claimed and illustrated in the accompanying drawing, in which:—

Figure 1 is a front elevation of the device.

Fig. 2 is a side elevation.

Fig. 3 is a sectional view on line 3—3 of Fig. 1.

The device comprises a pair of legs 1 and 2, which are hingedly connected at their upper ends, as at 3, said legs having their lower ends provided, as is usual, with points 4. Having one end fixed intermediate the ends of the leg 2 and lying in position to extend across the leg 1, is an arcuate bar 5, said bar having marked thereon graduations to indicate the distance between the points 4, and also having marked thereon adjacent its fixed end an indicating mark 6 in a line with the marking point of the leg 2, the purpose of which will appear later.

A bolt 7 is passed through the leg 1 and through a block 8, which is soldered to the adjacent face of the leg 1. Adjustably engaged on the bolt 7 is a thumb nut 9 which has its base of such diameter that it will overhang the bar 5, whereby when the nut is rotated in one direction it will bindingly engage the bar to hold the legs 1 and 2 in their set position so that the graduations can be read to ascertain the distance found between the points 4 of the legs.

Having its outer end fixed to the leg 1 and extending oppositely to the bar 5 in position to extend across the leg 1, is an arcuate bar 10 which is of less length than the bar 5, said bar also having marked thereon an indicating mark 11 which is placed adjacent the fixed end thereof and in a line with the marking point of the leg 1. It will be noted that the adjacent edges of the bars 5 and 10 slidably engage each other when the legs are spread apart or moved toward each other.

The bar 10 may be employed, in connection with the scale on the plate 5, as a vernier scale and may also be used as an additional width indicating scale, said bar 10 being marked with graduations designating tenths of a foot, whereby when one of the graduations thereon coincides with the mark 6 on the bar 5 it will indicate the distance between the points 4 of the legs.

It will be of course understood that when a graduation on the bar 5 coincides with the mark 11 on the bar 10, it will indicate the distance in inches between the points 4, and which is conventionally used by draftsmen, whereas the graduations on the bar 10 representing tenths of a foot are principally used by engineers who usually employ such scale.

What is claimed is:—

A divider having an arcuate bar fixed at one end to one of its legs and lying in position to extend across the other leg and having graduations thereon, a second bar secured at one end to the other leg and lying

in a position to extend across the first mentioned leg, said bars having their mutually adjacent edges disposed in sliding engagement, each of said bars having graduations marked thereon and each having marked thereon also an indicating mark in a line with the marking point of the leg to which the bar is attached in position to coincide with the graduations of the other bar, and

means for locking the legs against movement.

In testimony whereof, I affix my signature, in the presence of two witnesses.

WILLIE I. PALMER.
